UNITED STATES PATENT OFFICE

CLIFTON W. NIXON, OF NEW YORK, N. Y., ASSIGNOR TO NIXON VENDING AND CHANGE MAKING MACHINES, INC., OF NEW YORK, N. Y., A CORPORATION OF DELAWARE

CONTROL MECHANISM FOR COIN-CONTROLLED MACHINES

Application filed June 7, 1927. Serial No. 197,075.

My present invention relates to control mechanism for coin-controlled machines such as combined vending and change-making machines, vending machines and change-making machines; and in order to demonstrate the utility and practicability of my invention, I have shown in the accompanying drawings a preferred embodiment thereof in association with my improved vending and change-making machine, the related parts and mechanisms of which are more fully illustrated in my contemporaneously-pending applications for patents of the United States, Serial Numbers 197,076; 253,410; and 291,824, filed respectively on June 7, 1927, February 10, 1928, and July 11, 1928.

A main object of my invention is the provision of a simple and efficient control mechanism whereby the embodying machine, in accordance with its particular nature and class and upon the deposit therein of the prescribed coin, can be operated to sell merchandise and make change, or to sell merchandise alone, or to make change alone.

Another object of my invention is the provision of an improved carrier structure capable of being produced with a plurality of independently operable units, each of which 30 may be arranged to receive for its proper operation a different prescribed denomination of coin, the construction and arrangement of the carrier structure and component units being such that under the operation of the carrier structure the enlisted unit, i. e., the one receiving therein the deposited coin, will function to effect the operation of the machine containing the carrier structure.

A further object is the provision of a carrier structure of the foregoing character in which the units are self-cleaning, in which they may be individually and accurately adjusted, and in which they are entirely automatic in their operation, being arranged so 45 that their proper functioning cannot be de-

feated by reprehensible methods of operation calculated to procure the delivery of change or merchandise without making payment therefor.

A further object is the provision of a carrier structure in the form of a connector through which the power of a single operating handle may be transmitted to a plurality of power receiving elements. 50

A further object in view is to provide a carrier structure of this character which is so constructed and arranged that the individual units may be designed to accommodate one coin or more than one coin at a time. 55

It is also within the province of the present invention to provide an arrangement whereby the deposited coins will be carried a distance to cash receiving means and there automatically discharged. 60

Other objects will appear hereinafter. 65

The invention consists in the combinations and arrangements of parts hereinafter described and claimed.

The invention will be best understood by reference to the accompanying drawings 70 forming a part of this specification, and in which:

Fig. 1 is a side elevational view of the present improvements as embodied in my improved cigarette vending and change-making machine, parts being broken away and parts being shown in section; 75

Fig. 2 is a vertical sectional view, taken approximately on the line 2—2 of Fig. 1;

Fig. 3 is a top plan view of the carrier with 80 associated parts in section and broken away, this view being taken on the line 3—3 of Fig. 1;

Fig. 4 is a fragmentary plan view showing the connection between the carrier and dash 85 pot; and

Fig. 5 represents a sectional elevation, looking toward the "two dimes" unit of the carrier, parts being omitted to disclose more fully the character of the pull-bar for the 90

carrier structure as well as the members associated therewith.

With more particular reference to the accompanying drawings, the cigarette vending and change-making machine in which I have shown my present improvements as embodied by way of example comprises a cabinet 10 containing a rotary skeleton magazine structure 11 including an upper spider frame 12 with a ring plate 13 on which are mounted a series of change bank units 14, and including also a lower spider frame 15 with a ring plate 16 on which are mounted a corresponding series of holders 17 and 17' for containing, respectively, packages of cigarettes and packages of matches. For the discharge of the packages of cigarettes and matches into a delivery receptacle 18, there is an ejector mechanism 19 operated through link 20, bell crank 21, line rod 22, ball and socket joint 23, lift line shaft 24, sleeve 25, connector frame 26 and bell crank actuator 27 (of which in the present embodiment there are three). Said line shaft 24 at its upper portion has loose fit within rotary shaft 28 and the sleeve 25, which is pinned at 29 (Fig. 5) to line shaft 24, has sliding fit on rotary shaft 28, an arrangement which makes it possible, owing to the ball and socket joint 23, to turn the shaft 28 without effecting the operation of the ejector mechanism 19 and to operate any one of the bell crank actuators 27 without rotating said shaft 28. Each bell crank actuator 27 is operatively associated with coin pusher mechanism 30 by which the correct change is ejected from a change bank 14 into delivery receptacle 31 during the same operation that results in the delivery of cigarette and match packages into receptacle 18.

The magazine 11 is turned with the rotation of shaft 28 since the upper spider frame 12 is fastened to said shaft; and it is through the turning of the magazine that the holder containing the selected brand of cigarettes and the change bank corresponding therewith are brought into delivery position, so that upon a single operation of any one of the bell crank actuators 27, the selected package of cigarettes, a package of matches, and the correct change, if any change be due, will be delivered to the customer. The generator of the power for rotating the shaft 28 and for operating the bell crank actuators 27 comprises a manually operated handle 32 which is mounted to have rotary movement and depressible movement. Near its inner end, handle 32 turns in a bushing 33 on rocker 34 slidably embracing a bracket 35 in which the shaft 28 has turning movement. Rotary movement is transmitted from the handle 32 to shaft 28 through a pair of interconnected gears 36. Rocker 34 is fulcrumed on bracket 35 at 37 and the depression of the handle 32 causes hooked draw lever 38, pivoted to said

bracket at 39, to move rearwardly and upwardly on an arc, this result being attained because a bell crank 40, which is pivoted to said bracket at 41 and to said rocker with a lost motion movement at 42, is pivotally connected through a link 43 with the draw lever 38. A contractile spring 43' suitably connected between a fixed point on the cabinet and the free end of the rocker 34 may be employed as means for repositioning the rocker and handle in the event the customer, after depressing the handle, fails to move it upward to its elevated position.

The control mechanism, in its preferred form of construction as illustrated in the accompanying drawings, comprises a carrier structure composed of cross pieces 44 and 45 rigidly connected by vertically disposed strips 46, 47 and 48, which are arranged in lengthwise relation. The cross pieces 44 and 45 are equipped at their extremities with flanged blocks or shoes 49 having sliding fit between guide rails 50, of which as best shown in Fig. 2 there is one pair for each side of the carrier structure. The guide rails 50 are shown as held in place at their front ends by brackets 51 fixed upon an angle iron 52 on the inner face of the cabinet front 53, and at their rear ends by brackets 54 fixed in a plate 55 extending across the interior of the cabinet and in which the rotary shaft 28 is journaled. The strips 46 and 48, which extend well beyond the position of the rotary shaft 28, carry lateral projections 56; and coil contractile springs 57 connect the projections 56 with lateral projections 58 on the front brackets 51, whereby the carrier structure is retired against an abutment 59 secured upon the angle iron 52. The central strip 47, much shorter than the strips 46 and 48, has pivoted thereto at 60 the end of a hooked pull bar 61 adapted to be engaged by the draw lever 38 so as to advance the carrier structure against the tension of the springs 57 to its extreme position when the handle 32 is depressed. In this way the carrier structure is mounted to be drawn to an extreme position from the abutment 59 under each depression of the handle 32.

Associated with each of the strips 46, 47 and 48 is an independently operable coin-controlled unit including a head piece 62 and an action slide 63 cooperating together to form a coin space or pocket open at the top and bottom, both of said parts for this purpose being vertically disposed as shown and flanged as at 64. In the present exemplification, where the coin-controlled units are arranged to accommodate different denominations of coins, a coin space 65 shown in association with strip 46 is for the accommodation of two dimes; a coin space 66 in association with strip 47 is for the accommodation of a quarter; and a coin space 67 in association with strip 48 is for a half-dollar.

Each of the action slides is arranged in sliding flatwise contact with its supporting strip for limited movement toward and away from its cooperating head piece, the preferred 5 mounting arrangement for each action slide consisting in providing it with a fixed pin 68 having sliding fit in an elongated slot 69 in its supporting strip, and in forming it with a bifurcated rear end to provide furcations 70 adapted to fit astride the cross piece 45 and 10 slide in grooves 71 therein alongside the supporting strip. Each action slide is placed under tension by a pull spring 72, which connects the pin 68 with a pin 73 fixed on its 15 supporting strip, so as to be moved automatically toward its head piece and to have clamping action effect on a coin introduced into the coin space whereby in conjunction with its cooperating head piece to sustain 20 the introduced coin, it being observed in this connection that each of the head pieces is provided with a transverse pin 73' for sustaining the introduced coin by engaging its rim.

25 When the carrier structure is in station position, that is to say, when it is in engagement with the abutment 59, it is necessary to maintain the action slides in set position with the coin spaces adjusted to the precise dimensions necessary for receiving therein the prescribed coins. To this end means comprising stop pins 74 for setting the slides are adjustably arranged in an overhead frame plate 75 so as to depend therefrom in positions to be engaged by cooperating stop pins 76 projecting laterally from the action slides. This arrangement is such that as the carrier structure is retired to station position against the abutment 59, the pins 76 on engaging with the pins 74 will force the action slides away from their head pieces against the tension of the pull springs 72 and expand the coin spaces to their proper coin receiving dimensions, and that as the carrier structure is advanced from the abutment 59, disengaging the pins 76 from the pins 74, the springs 72 will call the action slides into position to clamp and sustain any coins introduced into the coin spaces. Moreover, under this arrangement, 40 when there are no coins in the coin spaces, the spring tensioned action slides, upon advancement of the carrier structure from the abutment 59, will move toward their head pieces to the full extent of the end play permitted in that direction by the slots 69 so that 45 the hooked draw bars 77 arranged on the action slides cannot be engaged with the bell crank actuators 27 when the carrier is advanced to its extreme terminal of movement from the abutment 59.

50 The draw bars 77 are fastened to the action slides by pivots 78 and have projecting ears 79 adapted to engage under stop pins 80 whereby to be maintained in position to slip into hooked engagement with the bell crank

actuators 27 when, owing to coins sustained in the coin spaces the action slides are rendered effective to engage the draw bars with the bell crank actuators on the advancement of the carrier to its extreme terminal of movement 70 under the depression of the handle 32. Each unit, therefore, is arranged to be rendered effective by a coin for engaging its draw bar 77 with a bell crank actuator 27.

75 It will be understood from an inspection of the drawings that each bell crank actuator is arranged to be pivoted during the retiring movement of the carrier toward the abutment 59; and it is to be observed in this connection that an engaged bell crank at the very beginning of its pivoting action, owing to the burden of the parts arranged to be operated thereby, will cause the connected action slide to be moved away from its head piece to the full extent of the end play permitted in that 80 direction by the slot 69, so that the sustained coin will be released to drop from the coin space. Provision is thus made for releasing the sustained coins at a predetermined place 85 distant from the station where they are introduced into the coin spaces. Under this provision, the station area where the coins are introduced is left clear for all slugs, spurious coins etc. which are incapable of entering the coin spaces, to fall upon a slideway leading to the outside delivery receptacle 31.

90 During the retiring movement of the carrier structure toward the abutment 59, the engaged draw bar 77 is forced out of engagement with the bell crank actuator by a stationary pin 81, but this action does not occur until after a push up pin 82, which rests on the sleeve 25 to rise therewith under the power stroke of the bell crank actuator, has engaged a ledge 83 on engagement with the draw lever 38. By this arrangement, the full 95 retractile force of the springs 57 is transmitted to the bell crank actuator momentarily prior to the disengagement therewith of the draw bar 77, with the result that the 100 change coins, merchandise and matches are discharged by a quick impulse transmitted through the bell crank actuator to the discharging mechanisms. and with the stem of the button key seated in an aperture 88 in the strip, so that as the head of the button key slides down the declivity 89 of the guide piece the spring will thrust the stem of the button key through the aperture 88 and into a keeper aperture 90 in the action slide. This operation takes place as the carrier approaches its extreme terminal of movement; and as the carrier commences its retiring movement the guide piece forces the button key in the reverse direction thereby unlocking the action slide. As shown in the drawings, the spring 86 has one end engaged with the button key and is supported at the other end on a post 91 fixed to the strip. The guide piece 87 is supported from the overhead frame plate 75.

The head piece for the two dimes unit is preferably mounted for pivoting movement alongside its strip and is provided with a weighted arm 92 arranged to induce its pivoting in order to effect a quick discharge of the two dimes which are sustained within the coin space one mounted upon the edge 25 of the other as shown in Fig. 5.

The movements of the carrier structure may be steadied through the employment of a dash pot or other suitable movement controlling apparatus. In the present exemplification, a dash pot 93 is shown as connected with the carrier, the connections including a rocker 95 arranged on a fulcrum pin 96 and having its opposite ends operatively connected, respectively, to the piston rod 97 and to a projection 98 on a cross plate 99 extending between the strips 46 and 48.

From the foregoing description, taken in connection with the accompanying drawings, it will be seen that an effective mechanism has been disclosed for transmitting movement from an operating handle to mechanism to be operated, and one which may comprise a plurality of independently operative coin-controlled units, each capable of serving as connector means for transmitting motion to mechanism to be operated and each capable of being arranged to accommodate a controlling coin of different denomination or size. It will also be seen that while the mechanism is of a compact nature it is nevertheless practically self-cleaning, the principal working parts all being relatively thin, vertically disposed, and surrounded by plenteous open space. Although terms such as coin, coins and coin-controlled, are employed throughout this application, it is not intended thereby that the application of the mechanism be limited thereto, as it is pointed out that metallic articles and other pieces may be prepared as means through which to effect the operation of the units.

While I have illustrated and described the preferred form of construction for carrying my invention into effect, this is capable of variation and modification without depart-

ing from the spirit of the invention. I, therefore, do not wish to be limited to the precise details of construction set forth but desire to avail myself of such variations and modifications as come within the scope of the appended claims.

Having thus described my invention, what I claim is:

1. Control mechanism of the kind set forth comprising a movable carrier structure; and power transmission means supported thereby including a coin clamping slide and means for varying the position of the slide relatively to the carrier structure consequent upon movement of the carrier structure. 75

2. Control mechanism of the kind set forth comprising a lengthwise movable carrier structure; cooperating members adapted to sustain a coin mounted on said structure; one of said members being mounted for automatic movement to vary its position in respect of the lengthwise movement of the structure, consequent upon movement of the structure, said movable member being arranged to have the extent of its automatic movement limited 25 by a coin sustained by said members. 90

3. In control mechanism of the kind set forth, a movable carrier structure; means associated therewith and therewith movable forming a coin space and including power 95 transmission means for varying the size of the coin space and adapted to be controlled by a coin in said coin space, and power receiving means to be moved in conjunction with the movement of said structure adapted 100 to be engaged by said transmission means when the latter is under the control of a coin.

4. In control mechanism of the kind set forth, a carrier structure mounted to travel 105 on guide rails to a predetermined point; means on the carrier structure forming a coin space including a relatively movable slide arranged to be held against retroactive movement by a coin in said coin space; and means on said slide adapted to be interconnected with power receiving means when said structure attains its predetermined point. 110

5. In control mechanism of the kind set forth, power receiving means, a carrier structure mounted to travel from station position to an extreme position; means on the structure forming a coin space including a relatively movable slide; a drawing element on the slide adapted to be interconnected with the power receiving means when the structure is in extreme position, whereby to move the power receiving means in conjunction with said structure toward station position, said slide being adapted by a coin in said 120 coin space to be held to position for causing said drawing element to be interconnected with the power receiving means. 125

6. Control mechanism of the kind set forth comprising a movable carrier structure; and 130

a plurality of independently actuatable power transmission devices carried thereby, each comprising a coin clamping slide and means for varying the position of the slide relatively to the carrier structure consequent upon movement of the carrier structure.

7. Control mechanism of the kind set forth comprising a carrier structure including a plurality of strips arranged in lengthwise relation; cross members connecting said strips; head members associated with said strips; slides slidably associated with said strips and cooperating with said head members; means for effecting the operation of said slides relatively to said head members; guide rails; and shoes on said cross members slidably engaging said guide rails.

8. Control mechanism of the kind set forth comprising a movable carrier structure including a strip; a cooperating head member and relatively movable slide associated with said strip to form a coin space; and various means for effecting the operation of said slide during the movement of said structure including first an operation to make the space of a prescribed coin receiving size, then an operation to establish a clamping action effect, and finally an operation to disestablish the clamping action effect.

9. Control mechanism of the kind set forth comprising a carrier structure mounted for movement to and from station position and including a plurality of strips; a head member and a relatively movable slide associated with each strip and arranged to form a coin space thereon; means for effecting the operation of each slide to make a coin space of prescribed size on movement of said structure to station position; and means for effecting the operation of each slide to insure a clamping action effect on a coin entered in the space on movement of said structure from station position.

10. In a coin-controlled machine, the combination with means for producing movement and means for receiving movement, of connector mechanism comprising a carrier structure arranged to be moved by said movement producing means; a plurality of independently actuatable power transmission devices supported by the structure, each comprising a coin clamping slide and means for causing the slide to move into position for clamping a coin consequent upon movement of the structure and means on each slide adapted, when a coin is clamped thereby, to interconnect with said movement receiving means to move the same in conjunction with said structure.

11. In a coin-controlled machine, the combination with means for producing movement and means for receiving movement, of connector mechanism comprising a carrier structure arranged to be moved by said movement producing means; a coin sustaining unit car-

ried by said structure and including a coin clamping slide and a spring for causing the slide to clamp a coin in the unit consequent upon movement of the structure; and means on said slide for engaging said movement receiving means when the slide clamps a coin, whereby to operate said movement receiving means in conjunction with the movement of said structure.

12. The combination, in a coin-controlled machine, of a power generator; a plurality of power receivers; a carrier structure arranged to be operated by the power generator; a plurality of coin sustaining units, corresponding in number with the power receivers, carried by said structure and each unit including a coin clamping slide and means for causing the slide to clamp a coin in its unit on movement of said structure; and means arranged on each slide, adapted to be rendered effective when a coin is clamped thereby, for operating its corresponding power receiver.

13. In control mechanism of the kind set forth, a carrier structure movably mounted and provided with a supporting strip; a head member and a slide associated with said strip and forming a coin space; a lost motion connection between said slide and strip establishing for the slide a limit of movement both toward and away from said head member; a resilient connection urging said slide toward said head member; and means arranged to effect a setting of said slide at a point between its limits of movement.

14. In combination, a frame; a carrier structure with a supporting strip mounted on the frame for movement to and fro; a head member associated with said strip; a slide forming a coin space with said head member and connected with said strip to have limited movement toward and away from said head member; a resilient connection urging said slide toward said head member; and stop means on said frame arranged to cause the operation of said slide against the tension of said resilient connection.

15. In combination, a frame; a carrier structure with a supporting strip mounted on the frame for movement to and fro between a station position and an extreme position; a head member and a slide associated with said strip and forming a coin space, said slide being connected to have limited movement toward and away from said head member; a resilient connection urging said slide toward said head member; stop means on said frame arranged to cause the operation of said slide against the tension of said resilient connection when said structure moves toward station position; and means adapted to function to lock said slide to said strip when the structure moves to its extreme position.

16. In a coin-controlled machine, the combination with a frame provided with a move-

- ment receiving element, of a carrier structure mounted on the frame to have movement to extreme position in relation to the receiving element and provided with a supporting strip having a head member; and a slide forming a coin space with said head member and carrying a pull bar adapted to cooperate with said receiving element, said slide being associated with said strip to have a lost motion movement toward and away from said head member and arranged to be rendered effective by a coin in said space to engage said pull bar with said receiving element on movement of said structure to extreme position.
17. The combination, in a coin-controlled machine, of a frame; a carrier structure mounted on the frame for to and fro movement; a head member and a slide associated with said structure and forming a coin space; said slide being mounted with a lost motion connection to move toward and away from said head member; a resilient connection urging said slide toward said head member; and cooperating means in connection with said frame and slide to adjust said slide to make said space of coin receiving size as the carrier structure moves in one direction and to permit said slide to have a clamping action effect on a coin within said space as the carrier structure moves in the opposite direction.
18. In a coin-controlled machine, the combination with a frame and an abutment, of a carrier structure mounted on the frame for movement to and from said abutment; a strip constituting part of said structure and provided with a head member; a slide forming a coin space with said head member and associated with said strip to have a lost motion movement toward and away from said head member; a resilient connection urging said slide toward said head member; and cooperating means on said frame and slide arranged to adjust said slide to make said space of coin receiving size as said structure moves to said abutment and to permit said slide to clamp a coin entered in said space as said structure moves from said abutment.
19. In control mechanism of the kind set forth, a carrier structure mounted for movement to and from station position and including a support; a head member and slide associated with said support and forming a coin space; a lost motion connection connecting said slide for movement toward and away from said head member; a resilient connection urging said slide toward said head member; and means for causing said slide to be moved against the tension of said resilient means as said structure moves to station position.
20. In control mechanism of the kind set forth, a carrier structure mounted for movement to and from station position and including a support; a head member and a slide

associated with said support and forming a coin space; a lost motion connection connecting said slide for movement toward and away from said head member; means arranged to move said slide against the tension of said resilient means as said structure moves to station position so as to provide for the clamping of a coin within said space by said slide as the carrier structure moves from station position; and means on the slide by which to move it in a direction to permit the release of the clamped coin.

21. In control mechanism of the kind set forth, a movable carrier structure; a head member and a slide associated with said structure to move therewith and forming a coin space; a lost motion connection connecting said slide for movement toward and away from said head member; and means arranged to be called into action during the movement of said structure for securing said slide against an exercise of its lost motion movement.

22. In control mechanism of the kind set forth, a movable carrier structure; a head piece and a slide associated with said structure to move therewith and forming a coin space; a lost motion connection connecting said slide for movement toward and away from said head piece; a resilient connection urging said slide toward said head piece; and means for positively locking said slide to prevent an exercise of its lost motion action against the tension of said resilient connection at one point during the movement of said structure.

23. In control mechanism of the kind set forth, a frame; a carrier structure movably mounted on the frame and including a strip; a head member and a slide associated with said strip and forming a coin space; said slide being mounted with a lost motion connection to move relatively to said strip; a spring pressed button key arranged to interlock with said slide and said strip; and a guide on the frame for controlling the functioning of said button key during the movement of said structure.

24. In a coin-controlled machine, the combination with an abutment and a carrier structure mounted for movement to and from said abutment, of contractile means arranged to reposition said structure against said abutment after each advancing action; and coin-controlled means mounted on said structure comprising a coin clamping slide and means for varying the position of the slide relatively to the structure upon advancement of the structure from said abutment against the action of the contractile means.

25. In combination, in a coin-controlled machine, movement receiving means, an abutment; a carrier structure mounted for movement to and from said abutment and including a plurality of strips arranged in length-

wise relation; contractile means arranged to reposition said structure against said abutment after each advancing action; and an independent coin-controlled unit associated with each of said strips and arranged to be rendered effective by a coin to be interconnected with said movement receiving means to move the same in conjunction with said structure.

10 In testimony whereof, I have signed my name to this specification.

CLIFTON W. NIXON.
